ABSTRACT OF THE DISCLOSURE

A new form of Y-junction circulator adapted to photolithographic construction techniques. Integral forms of split conductors and shunt resonating capacitors reduce the overall size of the lumped element circulator and extend its range of applicability into higher regions of the microwave spectrum.

BACKGROUND OF THE INVENTION

The present invention relates to a new form of Y-junction circulator adapted to photolithographic construction techniques. Integral forms of split conductors and shunt resonating capacitors reduce the overall size of the lumped element circulator and extend its range of applicability into higher regions of the microwave spectrum.

A common form of the Y-junction circulator consists of a ferrite core and a distributed constant resonator or center conductor. The dimensions of the center conductor are inversely proportional to the operating frequency of the circulator. With a disk-shaped resonator, for example, the diameter of the center conductor must be approximately equal to one-half the wavelength of the exciting signal, and if the frequency of the signal is halved, the diameter of the resonator must be doubled.

The prior art form of lumped element circulator, on the other hand, does not rely on dimensional resonance. In this form, which has been treated analytically in articles by Deutsch and Wieser, IEEE Transactions on Magnetics, vol. 2, No. 3, September 1966, pp. 278-82, and Konishi, IEEE Transactions on Microwave Theory and Techniques, vol. 13, No. 6, November 1965, pp. 852-64, and disclosed in patents to Roberts: 3,286,201 and Konishi: 3,335,374, the resonator includes a ferrite disk core and three tuned circuits, each containing a conductor and a discrete capacitive element. The conductors are radially disposed on the top surface of the core, with one end grounded in a manner providing three-fold symmetry. When connected to sources of high frequency energy, these conductors exhibit inductive reactances; therefore, the discrete capacitors are added to each circuit to achieve the resonance necessary for flux inducement in the core.

As is the case with the distributed constant form, the size of the lumped element circulator is substantially determined by its operating frequency, since the size of the discrete lumped inductive and capacitive elements decreases with decreasing wavelength. Though both circulator forms are frequency dependent, over a range of frequencies extending well into the gigahertz region the lumped element circulator is more compact than a distributed constant circulator operating at the same frequency.

However, those this size advantage in favor of the lumped element form exists up at least through X-band, in the present state of the art, it is nearly impossible to build discrete, non-integrated lumped elements which

2

operate at frequencies much above two gigahertz. Therefore, at frequencies above two gigahertz, the distributed constant form, in spite of its greater size, is normally used.

At the present time, extensive effort is being made in the art to combine, make smaller and reduce the cost of microwave components. It is particularly desirable, therefore, to achieve a practical lumped element circulator in the range at and above L-band which is more compact than the dimensionally resonant, distributed constant form.

SUMMARY OF THE INVENTION

The present invention concerns a new form of lumped element circulator in which the discrete reactances of the lumped element approach are combined into an integrated member analogous to the center conductor of the distributed constant form. The resulting integrated lumped element circulator, designed to be produced by photolithographic techniques, is reduced in size over both of the prior art forms, and offers lower cost, more opportunity for integration, and a range of operation extending well into the gigahertz region of the microwave spectrum.

Two versions of the integrated lumped element circulator are described. In a first embodiment, the necessary capacitance, added in shunt, is produced between adjacent conductor segments, one of which is grounded, by means of interdigitating conducting fingers formed as part of each conductor. In a second embodiment, a segment of each conductor is positioned in close proximity to a ground ring, thereby providing a direct capacitive connection to ground. Both versions are intended to be produced photolithographically.

BRIEF DESCRIPTION OF THE DRAWINGS

FIG. 1 is a diagrammatic representation of one embodiment of the present invention;

FIG. 2 is a sectional view taken along the line 2—2 in FIG. 1;

FIG. 3 is a perspective view of a segment of the circulator shown in FIG. 1;

FIG. 4 is a diagrammatic representation of a second embodiment of the present invention;

FIG. 5 is a sectional view taken along the line 5—5 in FIG. 4; and

FIG. 6 is a perspective view of a portion of the circulator shown in FIG. 4.

DETAILED DESCRIPTION

Referring to FIGS. 1-3, the circulator components include three conductors 11, 12 and 13, arranged in rotational symmetry on the upper face of substrate 20. The substrate is composed of a gyromagnetic material, commonly a ferrite or a composite alumina-ferrite. The middle segment of each conductor is divided into at least two split conductors, and the insulated crossing points of these split conductors are arranged as shown in FIG. 1 to induce a more uniform RF magnetic field inside the gyromagnetic material. As is discussed above, the conductors exhibit inductive reactance at the operating frequency, and series or shunt capacitors must be added to each circuit to achieve resonance.

In the first embodiment, shunt capacitors are composed of sets of conducting fingers 21 through 26 extending out from the outer portions of the conductors and proportioned so that fingers formed on facing sides of adjacent conductors interdigitate but do not touch. These sets of interdigitating, separated fingers produce capacitance between the two conductor segments of which they are part.

For example, finger set 23 forms a capacitor between the adjacent portions of conductors 11 and 13. The amount of capacitance is determined by the number of fingers, their dimensions, and the spacing between them.

Probes extending through eyelets 14, 15 and 16 connect one end of each conductor to ground plane 17 located beneath substrate 20. As FIG. 1 shows, the conductors are arranged so that their grounded ends are 120 degrees apart. Each ungrounded end is thus flanked by two grounded ends, and, since finger sets are present in every sextant, each ungrounded end is connected to ground through two symmetrically arranged capacitors.

Circulators built according to the teachings of this embodiment possess several advantages. First, since the capacitive and inductive reactances are part of the same member, they are produced simultaneously, in contrast to the discrete lumped element approach of Konishi and others. Second, since the capacitors are symmetrically connected from each input port to ground, they provide a maximum uniformity of port-to-port characteristics. Third, with the use of photolithographic techniques, this approach should be feasible up to X-band whereas the discrete lumped element approach using an assemblage of discrete elements is not believed to be feasible for operation above L-band. In the gigahertz range, circulators built as herein disclosed are a half to a full order of magnitude smaller than distributed constant circulators operating at the same frequency.

Circulators of the present type have been tested at L-band: the insertion loss is less than 1 db, maximum isolation is greater than 30 db and the 20 db bandwidth is 2 percent. The device tested has not been optimized with respect to bandwidth and insertion loss so that further development can be expected to improve on this performance. Photoetched series resonant circuits could be added to further broadband the circulator. The interdigital capacitors in this device lie within a circle of 0.5 inch diameter whereas an L-band distributed constant circulator has a diameter of several inches. A similar circulator designed for operation at 4 gHz. has a 0.125 inch diameter. At this size the circulator appears compatible with encapsulated semiconductor devices.

An alternative embodiment of the present invention is pictured in FIGS. 4-6. In this form ground ring 39 is contained in an annular groove 38 sunk into the upper face of substrate 40. Ground plane 37 is located beneath substrate 40 and is connected to ground ring 39 by probes extending through eyelets 34, 35 and 36. The three conductors 31, 32 and 33 are formed without the finger extensions appearing in the first embodiment. They are positioned in rotational symmetry as before, with one end of each acting as a port and the other suitably connected to ground ring 39.

Shunt resonating capacitance is included in this configuration at the points where the conductors pass over ground ring 39. Since ground ring 39 is sunk into the upper face of substrate 40, the segments 31a, 32a and 33a of the conductors lying above ground ring 39 may be brought as close as desired to it by properly setting the depth of groove 38. Each of these conductor segments forms one face of an air gap capacitor, and the underlying arc of ground ring 39 forms the other. The value of the capacitors may be regulated by varying the dimensions of the facing planes and the distance between them. This embodiment shares the cost, size and range of operation advantages of the first embodiment, and it too provides complete symmetry of the potential distribution.

It should be noted that other modifications of this embodiment are possible. Specifically, the sunken groove 38 may be eliminated if ground ring 39 is laid directly on the upper face of substrate 40 and a dielectric layer of air, silicon dioxide or other suitable material is maintained between the ring and the overlying conductor segments. A better alternative, and one particularly amenable to photolithographic techniques, recesses the ground ring 75

and the entire conductor pattern into the upper portion of the gyromagnetic substrate and then provides capacitance at the crossovers through the use of an inserted dielectric material as mentioned above. This embodiment is achieved through the use of one additional photolithographic mask which delineates the pattern to be etched into the substrate, and it provides excellent physical protection for the delicate crossover points.

It should further be noted that in both embodiments a second ferrite disk is normally, though not always, positioned above the area containing the split conductors, and that a second ground plane may be positioned on top of the structure to achieve compatibility with other portions of the circuit. When a second ground plane is present, eyelets 34, 35 and 36 are shifted out from under the overlying conductor segments so that ground connections may be conveniently made to both ground planes.

Other similar modifications will occur to those skilled in the art which do not depart from the spirit and scope of the present invention.

I claim:

1. A Y-junction circulator comprising a lower ground plane having a central axis, three coplanar conductors, each having one end grounded, radially arranged in rotational symmetry about the central axis above the ground plane so that their midpoints lie on the axis, their middle portions overlap, and the grounded end of a first conductor lies between the ungrounded ends of the second and third conductors,

a member of gyromagnetic material located between the ground plane and the conductors, and means for symmetrically producing a significant shunt capacitance associated with each conductor, said means comprising

at least one arcuate section of conducting material attached to and extending outward from both sides of the grounded end of each conductor in a plane parallel to the plane of the conductors, the dimensions of the section being chosen so that a portion of the conducting material comes into close proximity with the ungrounded ends of the adjacent conductors.

2. A circulator as defined in claim 1 including a second member of gyromagnetic material positioned above the plane of the conductors covering at least the overlapping middle portions of said conductors.

3. A circulator as defined in claim 1 including an upper ground plane positioned above the plane of the conductors.

4. A Y-junction circular comprising a lower ground plane having a central axis, three coplanar conductors, each having one end grounded, radially arranged in rotational symmetry about the central axis above the ground plane so that their midpoints lie on the axis, their middle portions overlap, and the grounded end of a first conductor lies between the ungrounded ends of the second and third conductors,

a member of gyromagnetic material located between the ground plane and the conductors, and means for symmetrically producing a significant shunt interdigital capacitance associated with each conductor, said means comprising

a plurality of conducting fingers lying substantially in the plane of the conductors attached to and extending outward from both sides of each conductor, along the outer portions of each conductor, the dimensions of each finger and the spacing along the conductors between the fingers being adjusted so that the fingers extending from both sides of the grounded outer portion of a first conductor and the fingers extending from the facing sides of the adjacent ungrounded outer conductor portions interdigitate but do not touch.

5. A Y-junction circulator comprising a lower ground plane having a central axis, three coplanar conductors, each having one end

grounded, radially arranged 120 degrees apart about the central axis above the ground plane so that their midpoints lie on the axis, their middle portions overlap, and the grounded end of a first conductor lies between the ungrounded ends of the second and third conductors,

a member of gyromagnetic material located between the ground plane and the conductors,

and means for symmetrically producing a significant shunt capacitance associated with each conductor, said means comprising

an annular ground ring positioned about the central axis between the gyromagnetic member and the plane of the conductors,

said ring being connected to the grounded end of each conductor and having an outer radius smaller than the distance from the midpoint of each conductor to its ungrounded end so that a segment of each conductor adjacent to its ungrounded end passes over an arcuate portion of the ground ring, and

means for maintaining a particular value of capacitance between the ground ring and the overlying segment of each conductor.

6. A circulator as described in claim 5 wherein said

means for maintaining a particular value of capacitance between the ground ring and the overlying segment of each conductor comprises

an annular groove included in the upper face of the gyromagnetic material and containing the ground ring,

the depth of the groove being adjusted so that the perpendicular distance between the segment of each conductor lying above the exposed ground ring and the ground ring produces the particular capacitance.

7. A circulator as defined in claim 5 wherein said means for maintaining a particular value of capacitance between the ground ring and the overlying segment of each conductor comprises a layer of dielectric material of predetermined thickness positioned between the ring and the overlying segment.
